(57) **CLAIM**

I claim the ornamental design for a crawfish boil sink, as shown and described.

DESCRIPTION

FIG. 1 is a front elevation view of the sink of the present invention;

FIG. 2 is a right side elevation view thereof;

FIG. 3 is a left side elevation view thereof;

FIG. 4 is a back side elevation view thereof;

FIG. 5 is a top plan view thereof; and,

FIG. 6 is a bottom plan view thereof.

The broken lines showing features on the rear side are included for the purpose of illustrating a portion of the sink that forms no part of the claimed design.
